DESIGN FOR A KEEPER FOR A DRAWBOLT OR THE LIKE

Albert J. Komenak, Stamford, Conn., assignor to
The Excelsior Hardware Company, Stamford,
Conn., a corporation of Connecticut

Application November 29, 1939, Serial No. 88,562

Term of patent 7 years

To all whom it may concern:

Be it known that I, Albert J. Komenak, a citizen of the United States, residing at Stamford, in the county of Fairfield and State of Connecticut, have invented a new, original, and ornamental Design for Keeper for a Drawbolt or the like, of which the following is a specification, reference being had to the accompanying drawing, forming part thereof.

Figure 1 is a front view, Figure 2 is a side elevation, Figure 3 is a plan view, Figure 4 is a bottom view, and Figure 5 is a perspective view of a keeper for a drawbolt or the like showing my new design.

I claim:

The ornamental design for a keeper for a drawbolt or the like, substantially as shown.

ALBERT J. KOMENAK.
